UNITED STATES PATENT OFFICE

91,496

DESIGN FOR A COUNTER DISPLAY CASE

Franklin J. Petzke, Minneapolis, Minn.

Application December 4, 1933. Serial No. 49,932

Term of patent 3½ years

To all whom it may concern:

Be it known that I, FRANKLIN J. PETZKE, a citizen of the United States, residing at Minneapolis, in the county of Hennepin and State of Minnesota, have invented a new, original, and ornamental Design for a Counter Display Case, of which the following is a specification, reference being had to the accompanying drawing, forming a part hereof.

I claim:

The ornamental design for a counter display case, as shown.

FRANKLIN J. PETZKE.
